Henry W. Henley.

UNITED STATES PATENT OFFICE.

HENRY W. HENLEY, OF NEW YORK, N. Y., ASSIGNOR TO ALBERT PALMER, OF JERSEY CITY, NEW JERSEY.

VENTILATING-BEDSTEAD.

Specification of Letters Patent No. 26,946, dated January 24, 1860.

To all whom it may concern:

Be it known that I, HENRY W. HENLEY, of New York, in the county of New York and State of New York, have invented a new and Improved Ventilating-Bedstead; and I do hereby declare the following to be a full and exact description of the same, reference being had to the accompanying drawings and to the letters of reference 10 marked upon the same.

A shows an ordinary bedstead; B the mattress formed of a series of serrated sections; C the clock-work by which the fans are or fanning apparatus is operated.

15 D D are two fans placed directly beneath the mattress and operated by the clock-work C.

The nature of my invention consists in attaching to an ordinary bedstead, one or 20 more fans, or a fanning apparatus, which being used in conjunction with a mattress formed of a series of serrated sections combined (as shown at B) and being driven or propelled by means of clock-work (C) shall 25 operate in such a manner that a current of air shall constantly be driven up through the serrated mattress as to ventilate the bed clothing and keep the person sleeping perfectly cool and comfortable.

30 To enable others skilled in the art to make and use my invention I will describe its construction and operation.

To an ordinary bedstead A, a clock-work is attached in any desired position beneath 35 the slats of the same. Connected with this

clock-work by means of the shaft E, and operated by the same, are the two fans (D D), placed directly beneath the mattress composed of a series of serrated sections (B). A valance placed around the bottom of the 40 bedstead and shown in the model accompanying this specification serves to confine the air, which is driven through the serrated mattress and as before stated answers the purpose of ventilating the bed clothing and 45 keeping the person or persons sleeping cool and comfortable. The apparatus being thus arranged, the clock-work being wound up the fans will be operated in such a manner as to produce the desired effect. 50

I do not however intend to confine my invention to the use of oscillating fans as herein shown. I am fully aware that fans having a rotary motion may be used, also 55 fans that vibrate.

Many substitutes may be used for the mattress formed by combining the serrated section, as a serrated sacking &c.

What I claim as new and desire to secure by Letters Patent is— 60

Combining one or more fan or fans, with the mattress formed of the serrated sections or its equivalent device, when the same shall be arranged and operated in the manner described and for the purpose specified.

HENRY W. HENLEY.
